UNITED STATES PATENT OFFICE

EGBERT H. GOLD, OF EVANSTON, ILLINOIS; MARGARET JAYNE GOLD AND BISCAYNE TRUST COMPANY EXECUTORS OF SAID EGBERT H. GOLD, DECEASED

SUPPORTING MEANS FOR FLEXIBLE PIPE MECHANISM

Application filed September 26, 1927. Serial No. 222,034.

This invention relates to supporting means for flexible joint mechanism, and more particularly to improved means for reinforcing the connections whereby the end train pipe valve is supported from the car train pipe, and the flexible pipe structure is suspended from the end train pipe valve.

As is well known, in car heating systems, a continuous steam supply pipe extends throughout the length of the train beneath the several cars. This supply pipe comprises a car train pipe extending beneath the length of each car and supported therefrom, and a pair of flexible pipe structures, one of which is suspended from each end of this car train pipe and adapted to be connected by means of suitable coupling means with a corresponding flexible pipe structure at the end of the adjacent car. Usually an end train pipe valve for controlling the flow of steam from the car train pipe is attached to the end of the car train pipe and the flexible pipe structure is suspended from the end train pipe valve. Ordinarily the end of the car train pipe is threaded into a horizontally projecting passage at one side of the end train pipe valve, and the valve is supported from the pipe by means of this threaded connection. In a similar manner, the upper section of the flexible pipe structure is threaded into a downwardly projecting opening or passage in the valve housing, and the flexible pipe structure is supported from the valve by means of this threaded connection. Since both the flexible pipe structures and the end valve are massive and quite heavy, in order to withstand the rough service to which they are subjected, considerable strain is thrown upon the threaded connections in order to force these respective members from the car train pipe. The threaded connections are apt to become strained and weakened, and sometimes either the flexible pipe structure or the end valve, or both, break off and are lost, besides rendering the heating system inoperative.

The present invention is designed to provide reinforcing means for the threaded connections hereinabove described, and also prevent the loss of the flexible pipe structure or the valve in case breakage should occur. In gen-

eral, specially designed clamping members are provided which engage the adjacent end portions of the connected members at positions somewhat removed from the inter-engaged threaded portions so as to relieve the threaded portions of a part of the supporting strain, and to hold the two members connected with one another in case breakage of the threaded connections should occur.

The particular objects and advantages of this invention will be more apparent from the following detailed description of certain approved forms of apparatus designed to perform the functions hereinabove noted.

In the accompanying drawings:

Fig. 1 is a side elevation of one of the assembled conduit structures.

Fig. 2 is an enlarged detail view of the connection between the flexible pipe structure and the end train pipe valve, one-half of the auxiliary clamping means being removed.

Fig. 3 is a perspective view of one of the clamping members, for example, the one removed from the disclosure in Fig. 2.

Fig. 4 is an enlarged elevation of the end train pipe valve, the reinforcing extension formed thereon being shown in vertical section.

Fig. 5 is an elevation similar to Fig. 4, showing a preferred form of the invention, a part of the clamping member being broken away.

Fig. 6 is a vertical section, taken substantially on the line 6—6 of Fig. 5.

Referring first to Figs. 1, 2, 3 and 4, the car train pipe is indicated at A, the end train pipe valve at B, and the flexible pipe structure at C.

The end valve B may be of any usual form, and as here shown has a laterally projecting extension 1 into which the end 2 of the pipe A is threaded, as shown at 3. This ordinarily forms the only means by which the valve is supported from the car train pipe. The housing of the valve B also has a downwardly extending projection 4 into which the

upper section of the flexible pipe structure C is threaded, as indicated at 5, the flexible pipe structure usually being suspended by means of this threaded connection. The flexible pipe structure C is built up of a plurality of metal-

lic pipe sections swiveled together in such a manner that a universal bodily movement of the coupler 6, through which connection is made with an adjacent car, is permitted in 5 practically any direction so as to allow for the relative movements of the two cars without breaking or unduly straining the conduit structure. This flexible conduit structure C may take a variety of forms, the one here 10 shown being merely an example, but in any case the upper section thereof will be suspended from the valve B, or from the end of train pipe A, usually by a threaded connection, such as indicated at 5 in Fig. 2.

15 It will be apparent that the members B and C will be of considerable weight, and that the threaded connections between the train pipe and valve, and between the valve and flexible conduit will be under considerable stress. These threaded connections (particularly the one between the car train pipe A and the end train pipe valve B) remain 20 in service for great lengths of time and are apt to rust and become weakened so that 25 in time the weight of the suspended parts, together with the sudden stresses caused by the jerking of the cars may be sufficient to break these connections and permit the suspended parts B or C to drop. This will not 30 only render the heating system inoperative, but the broken parts may be lost, and these parts are apt to fall into and derange switch mechanism, or otherwise cause a wreck or other property damage. The improvements 35 hereinafter described are designed to reinforce and strengthen these threaded connections, and to temporarily suspend the parts in case breakage of the threaded connections should occur.

40 The inter-engaging end portions of the valve B and conduit structure C are usually provided with outstanding collars or flanges having a regular polygonal periphery for engagement by wrenches when the parts are being screwed together, these flanges being 45 indicated at 7 and 8, respectively. A pair of similar clamping collars 9 (one of which is indicated in perspective in Fig. 3, and one of which is indicated in applied position in 50 Fig. 2), are adapted to be fitted about the inter-engaging end portions of the members B and C, these clamping members 9 having inwardly extending semi-annular flanges 10 and 11 adapted to engage behind the collars 7 and 8. Each of the members 9 is provided 55 with a pair of outstanding ears 12 which are adapted to be clamped to the corresponding ears on the other member 9 by means of 60 bolts or other suitable fastening members 13. It will be apparent that the collar formed by the two clamping members 9 serves to assist in supporting the weight of the flexible conduit structure C, resists bending strains, 65 and will serve to support the structure C

in case the threaded connection 5 should become broken.

As best shown in Fig. 4, the lateral extension 1 of the valve B, into which the end 2 of pipe A is threaded, as shown at 3, is formed with an extension, as indicated at 14, which terminates in a collar 15 closely engaging about the pipe A at a location somewhat remote from the threaded connection 3. The portion 14 of this extension may be in the 70 form of a continuous cylindrical tube, as here shown, or may be simply a plurality of spaced fingers or bars. It will be apparent that this extension 14 and collar 15 serve to take a 75 large portion of the bending strain off from the threaded connection 3 and to distribute the weight of the suspended members B and C along a more extended portion of the pipe A. In case the threaded connection 3 should become broken, this extension 14 will serve 80 to temporarily support the valve B, and the conduit structure C carried thereby.

The preferred form shown in Figs. 5 and 6 is adapted for those installations wherein provision is made for the lateral movement 90 of the train pipe A and the members supported therefrom, in company with the coupler head or draw-bar by means of which the cars are connected. In some systems, the end 95 portions of the pipe connections on the cars are so mounted that they will move laterally in company with the coupler head in order to avoid damage caused by the engagement of these parts. Such a construction is disclosed in the patent to Davidson 985,149 100 granted Feb. 28, 1911. Referring now to Figs. 5 and 6, 16 is a hanger or sill extending transversely beneath the end portion of the car, and 17 is a support or carriage 105 slideable along this sill transversely of the car. The end portion of train pipe A is supported in a block or cradle 18 on carriage 17, and the laterally projecting portion 1 of valve body B is also supported on the carriage 17, for example by having a portion of the flange 19 rest directly upon the carriage. The pipe A is held in place by means of a clamp 20 secured to the cradle 18 and engaging over 110 the upper portion of the pipe. According to the present improvement, an extension 21 115 is provided on the clamp member 20, this member 21 extending over the flanged collar 19 on the valve housing and having a downwardly projecting portion 22, preferably provided with extended fingers 23 adapted to 120 clamp about the portion 1 of the valve. A sufficient clearance is provided beneath the extension 21, as indicated at 24 and 25, to permit the necessary movement of flange 19 125 longitudinally of pipe A, as the pipe expands or contracts. The clamp 21 serves to transfer a considerable portion of the supporting stress of members B and C directly to the support or carriage 17 instead of having all of this stress thrown upon the threaded 130

end of pipe A. Furthermore, in case the threaded connections should break, the clamp 21 will serve to hold the valve B in engagement with carriage 17 and prevent the loss of the suspended members.

It will be understood that the clamping device shown in Figs. 2 and 3 for supporting the apparatus C from the valve B would be used in connection with the disclosure of Figs. 5 and 6, in the same manner that it is used with the first-described auxiliary support for valve B, as shown in Figs. 1 and 4.

In some installations, the end valve B is not located directly at the end of train pipe A, and the flexible structure C is supported from the downward end portion of pipe A. The clamps 9 could be applied to such a construction, the proportions of the parts being modified as might be found necessary.

The extension 14, as shown in Figs. 1 and 4, need not be formed as an integral portion of the housing of valve B, but may be rigidly secured to the lateral extension 1 of the valve housing in any suitable manner.

I claim:

1. A supporting mechanism for a car train pipe and the end train pipe valve connected therewith comprising a support carried by the car, a cradle carried by the support on which the pipe is adapted to rest, there being an outwardly extending flange on the pipe-engaging end of the valve, said flange being adapted to rest on the support adjacent the cradle, and a clamping member secured to the cradle and having a portion adapted to engage over the pipe and a connected portion adapted to extend over the valve and provided with a downwardly projecting arcuate flange adapted to engage down behind the flange on the valve.

2. A supporting mechanism for a car train pipe and the end train pipe valve connected therewith comprising a hanger on the car and a support slideable along the hanger, the pipe and adjacent end of the valve being adapted to rest on the support, and a clamping member secured to the support and having a portion adapted to engage over the pipe and a connected portion adapted to engage over the valve to relieve the strain on the inter-engaged portions of the pipe and valve.

3. A supporting mechanism for a car train pipe and the end train pipe valve connected therewith comprising a hanger on the car and a support slideable along the hanger, the pipe and adjacent end of the valve being adapted to rest on the support, and a clamping member secured to the support and having a portion adapted to engage over the pipe and a connected portion adapted to extend over the valve and provided with a downwardly projecting arcuate flange adapted to extend down behind an outwardly projecting flange on the valve.

4. A supporting mechanism for a car train

pipe and the end train pipe valve connected therewith comprising a hanger on the car and a support slideable along the hanger, a cradle carried by the support on which the pipe is adapted to rest, there being an outwardly extending flange on the pipe-engaging end of the valve, said flange being adapted to rest on the support adjacent the cradle, and a clamping member secured to the cradle and having a portion adapted to engage over the pipe and a connected portion adapted to extend over the valve and engage down behind the flange.
